UNITED STATES PATENT OFFICE.

CALEB BRINTON, OF PORTLAND, OREGON.

DESIGN FOR AN EMBLEM OR BADGE.

No. 39,367.

Specification for Design.

Patented June 23, 1908.

Application filed February 8, 1906. Serial No. 300,191. Term of patent 7 years.

To all whom it may concern:

Be it known that I, CALEB BRINTON, a citizen of the United States, residing at Portland, in the county of Multnomah and State of Oregon, have invented a new, original, and ornamental Design for an Emblem or Badge, of which the following is a specification, reference being had to the accompanying drawings as forming a part thereof.

The figure of the drawing is a plan view showing the design of the emblem or badge.

I claim:

The ornamental design for an emblem or badge, as shown.

CALEB BRINTON.
